UNITED STATES PATENT OFFICE.

LEWICKI J. LEON, OF WEST CHICAGO, ILLINOIS.

DESIGN FOR A BIRD CAGE.

Application filed January 30, 1928. Serial No. 25,078. Term of patent 14 years.

To all whom it may concern:

Be it known that I, LEWICKI J. LEON, a citizen of the United States, residing at West Chicago, in the county of Dupage and State of Illinois, have invented a new, original, and ornamental Design for Bird Cage, of which the following is a specification, reference being had to the accompanying drawing, forming part thereof.

The figure is a front elevational view of a bird cage, showing my new design.

I claim:

The ornamental design for a bird cage, as shown.

LEWICKI J. LEON.
